Primary Examiner — Lakiya G Rogers*Assistant Examiner* — Altaira J Swangin(74) *Attorney, Agent, or Firm* — Reilly Intellectual Property Law Firm(57) **CLAIM**

The ornamental design for a dispensing device, as shown and described.

DESCRIPTION

FIG. 1 is a perspective view of a dispensing device showing our new design;

FIG. 2 is a top view of FIG. 1;

FIG. 3 is a front view of FIG. 1;

FIG. 4 is a bottom view of FIG. 1;

FIG. 5 is a left side view of FIG. 1;

FIG. 6 is a right side view of FIG. 1;

FIG. 7 is a rear view of FIG. 1;

FIG. 8 is an exploded front view of FIG. 1; and,

FIG. 9 is an exploded rear view of FIG. 1.

The dashed lines of FIGS. 1, 3, 7, 8 and 9 are included to show measuring environment that forms no part of the claimed design.

1 Claim, 6 Drawing Sheets(56)
